CLAIM

The ornamental design for a bath accessory base, as shown and described.

DESCRIPTION

FIG. 1 is a top, front, and right side perspective view of a first embodiment of a bath accessory base showing my new design;

FIG. 2 is a front elevational view of FIG. 1;

FIG. 3 is a left side elevational view of FIG. 1;

FIG. 4 is a right side elevational view of FIG. 1;

FIG. 5 is a top plan view of FIG. 1;

FIG. 6 is a bottom plan view of FIG. 1;

FIG. 7 is an additional top, front, and right side perspective view of FIG. 1, with the broken-line disclosure of a towel ring being for illustrative purposes only and forming no part of the claimed design;

FIG. 8 is another additional top, front, and right side perspective view of FIG. 1, with the broken-line disclosure of a toilet paper holder being for illustrative purposes only and forming no part of the claimed design; and,

FIG. 9 is a top, front, and right side perspective view of a second embodiment of a bath accessory base showing my new design, with the broken-line disclosure of a towel bar holder being for illustrative purposes only and forming no part of the claimed design.
